(57) CLAIM

The ornamental design for a ribbon shaping bodycare jumpsuit as shown and described.

DESCRIPTION

FIG. 1 is a front perspective view of a ribbon shaping bodycare jumpsuit showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The broken lines crossing claimed surfaces represent stitching, which does form part of the claimed design. The broken line showing of the person depicts environment, and forms no part of the claimed design.
